S.B. Minnich,

Horse Power.

No 84,434.

Patented Nov 24, 1868.

United States Patent Office.

SIMON B. MINNICH, OF LANDISVILLE, PENNSYLVANIA.

Letters Patent No. 84,434, dated November 24, 1868.

WINDLASS AND HORSE-POWER.

The Schedule referred to in these Letters Patent and making part of the same.

To all whom it may concern:

Be it known that I, SIMON B. MINNICH, of Landisville, in the county of Lancaster, and State of Pennsylvania, have invented new and useful Improvements on Machines for Hoisting up Hay or other weighty matters, and readily applied as a horse-power on the farm; and I do hereby declare that the following is a full, clear, and exact description of the construction and operation of the same, reference being had to the accompanying drawings, making a part of this specification, in which—

Figure 1 is a perspective view of my windlass, with the improvements in place.

Figure 2, a plan view of the same, employed as a horse-power.

The other figures being the detached portions separately illustrated, which, combined, constitute my machine or invention.

The nature of my invention consists in the arrangement of the revolving cylinder and cog-like locking-device, revolving on a central standard or axle; said cylinder, with its upper cog-like flange, also forming a drum, the lower flange being provided with chambers, for the reception of from eight to twelve radiating arms, these arms being provided with adjustable hooks, over which a cord or chain winds or acts; the whole being operated by a horse, attached to a long lever or sweep.

To enable others skilled in the art to make and use my invention, I will describe its construction and operation, referring to the detached pieces and their arrangement.

A shows a central axle, with foot-pieces Z, forming the standard, the lower portion of which has a greater diameter in the offset or shoulder.

Between A and a are recesses p, at four points, opposite each other, to receive corresponding projections, shown on the under side, D', of an annular piece, D, the upper side of which is also provided with a series of cog-like projections.

This ring D fits into the head or hub C, which has a flange projecting, the upper face of which has a similar series of cog-like lugs, n, or stops, around its outer periphery, on a level with those on the inner ring D.

This hub C has a flange below, which is chambered for the reception of long arms, 8 or 12, radiating from the centre.

The intermediate space of the hub, between the projecting flanges, also forms a winding-drum, to which a cord may be attached by a proper loop or fixture.

The arms K are each provided with an adjustable hook, L, adapted either for a rope or to the links of a chain.

L' shows one with a perforation for a piece of gum, m, to confine the rope, in case it is slackened or receives a sudden jerk, the cord or rope W, or its equiva-

lent, held by and is wound on or off from the hook L, when hoisting.

When used to drive a corn-sheller or the like, a trunk, Q, fig. 2, may be employed in connection with the same.

The rope or chain W, tight on the hooks, leads at one point over a horizontal roller, t, and flanged pulley U, thence down around a driving-drum pulley, r, and over the same, and back over the lowered portion of the horizontal roller or pulley U, and the vertical roller S, to the hook L, on the arm next, as shown by fig. 2.

To the shaft of the drum-pulley there is, on the outside of the trunk, a strap or belt-pulley, v, which connects with the corn-sheller, or its like machinery, constituting a horse-power.

On the upper portion of the standard, around a, sets the sweep and stop-head E. This has a prolongation on two sides, opposite each other.

The rear portion has square holes, 1 and 2, for the reception of the guide-rod J and bevelled click-bolt I. This click-bolt sets loosely in the square opening 2, and projects so as to come between the cog-like projections on the ring D, which ring being stationary, would lock the outer hub C, but the bolt I has one side rounded off, so that as the bolt is being carried round, it rises by sliding over each projection, when moved in one direction, by the turning of the sweep-head E; but to prevent a backward motion, the flat side of the bolt I comes up squarely, and locks, so as to prevent a retrograde motion.

This bolt is best when made of hard wood, which will resist all ordinary force, and had better break when extraordinary force is applied than to endanger the machinery, as might happen if a strong iron bolt were used.

The forward portion of head E has a square hole, 3, for the reception of the lock and hook-bolt G. This has an offset that comes down between the outer series of cog-like stops n, on the hub C, and has a hook, g, which engages below the flange, on the upper part of the hub aforesaid.

This bolt G is connected with a lever, H, hinged in a slot, 4, on the head F, set on the rear of the sweep or horse-lever Y, which latter head has also a side slot, 5, for the leading-arm X, in which said arm is reversible.

The sweep-head E is further prolonged into a box, for the horse-lever or sweep Y.

Figure M shows a modified lock-arrangement or ring, having only stop-cogs below, and an octagonal open centre, which slides on an eight-cornered portion to be made on the lower end of the head E. This ring M, by means of three or four chains or cords, connected with the lever H, can be raised up to disengage the hub C from the action of the sweep, as the

raising of the hook-bolt G does; but it would lock upon all the cog-like projections of the hub, instead of at one point only, as when the bolt C is used. In that case, the hook-bolt C can be dispensed with.

P is a washer, under the nut O, to confine the sweep-head E on the top of the central shaft or standard.

The operation is readily understood. The winding-rope W is carried through a trunk, over pulleys, to elevate the article to be hoisted. The lever H, connected with the bolt G, has a cord over a loop or pulley, on the rod J, leading to the hand of the operator, who, in order to stop the winding, draws the bolt, when the action of the hub and radiating arms stop, by separating the connection between the sweep-head and winding-apparatus.

To reverse the action of the machine, it is only necessary to change the position of the click-bolt I, so as to bring the rounded face on the opposite side.

This machine, however tedious to describe, is nevertheless simple. No actual cog-gearing is used. The cog-like stops differ substantially, and do not mesh or operate as cog-gearing.

The sweep itself is common, apart from the peculiar arrangement of the sweep-head.

I am aware also that a vertical windlass is not new, but, under substantially different combinations and arrangement, I deem this a useful machine on the farm, for elevating hay and the like. It is simple, durable, and efficient as a windlass or horse-power.

I am aware, also, that capstan-barrels or hubs are used, with sockets for inserting a movable lever, for

winding on a drum. Such I deem substantially different from the arrangement I claim.

What I claim as my invention, and desire to secure by Letters Patent, is—

1. The construction of my hub or drum C, with its lower flange and open chamber Y, when the upper flange is provided with cog-like stops n on its upper face, arranged and operated substantially in the manner and for the purpose specified.

2. Independent rings D M, provided with cog-like stops n, in combination with the drum C, arranged in the manner and for the purpose set forth.

3. The adjustable sliding hooks L, on the radiating arms K, in combination with the chambered hub or drum C, when operated in the manner and for the purpose described.

4. The arrangement of the sweep-head E, when provided with slots 1, 2, and 3, for the reception of the rod J, click-bolt I, and hook-bolt G, in the manner and for the purpose specified.

5. A loose, wooden click-bolt, I, bevelled, and operating, in combination with the cog-like stops n, in the manner and for the purpose set forth.

6. In combination with the hub or drum C, radiating arms K, and hooks L, the arrangement of the trunk Q, with its vertical roller S and horizontal pulleys t u r e; all arranged in the manner and for the purpose specified.

Witnesses: SIMÓN B. MINNICH.
